UNITED STATES PATENT OFFICE.

W. H. ORR, OF MARTINS FERRY, OHIO, ASSIGNOR TO WM. M. GRIFFITHS & CO., OF SAME PLACE.

MACHINE FOR CLEANING GRAIN.

Specification forming part of Letters Patent No. 20,923, dated July 13, 1858; Reissued November 1, 1859, No. 845.

To all whom it may concern:

Be it known that I, WILLIAM H. ORR, of 5
Martins Ferry, in the county of Belmont
and State of Ohio, have invented an Im-
provement in Machinery used for Threshing
and Cleaning Wheat and other Small Grain;
and I do hereby declare that the following
is a full and exact description thereof, ref-
erence being had to the annexed drawing,
10 forming a part of this specification, like
letters referring to like parts.

Figure 4 is a side elevation. Fig. 5 is a 15 perspective section. Fig. 3 is an end elevation. Figs. 1 and 2 represent an arrange-
ment of certain parts hereafter described
differing slightly from Figs. 4 and 5.

In this, as in many other machines used 20 for a like purpose, the threshing is effected
by passing the unthreshed grain beneath a
cylinder furnished with teeth or spikes, and
which is made to revolve above a fixed con-
cave in which teeth or spikes are also in-
serted. After leaving the threshing cylin-
der, by the force communicated thereby, the
25 straw and threshed grain are thrown up
the inclined chute C, the greater portion of the
grain on arriving at a, by its gravity, being
precipitated down the chute D, whence it
falls upon the system of riddles, screens, etc.,
30 in the laterally vibrating shoe G, and is sub-
jected to the action of the blast from the
fan F. The straw after arriving at the top
of the chute C is thrown upon the endless
carrier E by the agency of which it is car-
35 ried off to the place of discharge L.

The carrier E is constructed of straps or 40 cords f, f placed at suitable distances apart
and traveling in grooves in the revolving
rollers H and Q; or the cords of the carrier
E, instead of passing over the roller H, may
be made to pass over an independent roller
or pulley (Figs. 1-2) in which case, the
straps or cords of the carrier E, are pro-
vided with slats or bars b b, (Figs. 1-2)
45 placed at suitable distances apart, and at
right angles to the direction of said straps
or cords, the spaces between the cords f f in
the former arrangement, and between the
cords f f and slats b b in the latter arrange-
50 ment, allowing the grain remaining in the
straw, on its way to the place of discharge L,
to fall upon the inclined return bottom M,
whence it is discharged upon the shoe G.
This grain, together with that previously

separated from the straw at a falling upon 55
the laterally vibrating shoe G, at or near
the point c, is subjected to the action of the
blast from the fan F, the greater portion of
the grain, by the assistance derived from the
vibrating motion of the shoe, passing 60
through the perforations or meshes in the
riddle N, and falling upon the screen d upon
which the clean grain is carried into the
discharge spout I—the smaller heavy im-
purities passing through the meshes in said 65
screen, and being carried on the inclined bot-
tom of the shoe G into the tailing spout J,
the chaff and other light foreign matter, in
the mean time, by the blast from the fan F
being blown off at the surface of the riddle 70
N in the direction of P. As the blast from
the fan F acts with greater intensity at that
part of the shoe G placed in immediate con-
tact than at other points farther removed
therefrom, a portion of the grain, according 75
to its gravity, is carried along with the chaff,
and deposited at various points on the sur-
face of the riddle. Hence, in order to effect
perfect separation, a considerable length of
riddle is required.

In machines heretofore constructed, in 80
order to effect perfect separation, and to
prevent a portion of the grain from being
blown over with the chaff and lost, it has
been the practice to extend the riddle N
somewhat beyond the point at which the 85
blast acts with a force sufficient to blow off
all the chaff, and other light substances.
Under this arrangement the apertures near
the tail of the riddle N have a tendency to 90
become choked which prevents the grain
carried to that point from passing into the
shoe G, and causes an accumulation of chaff
and other foreign matter, together with a
portion of the grain near the tail of the 95
riddle N. This difficulty in machines here-
tofore constructed has been generally obvi-
ated by an attendant stirring the chaff which
accumulates near the tail of the shoe G with
a stick, by which means the apertures in the 100
riddle near the tail of the shoe are kept open,
the remaining grain, under the circum-
stances, readily passing through said aper-
tures, while in consequence of being thus
agitated and divided the chaff is blown off 105
the tail of the riddle at P by the slight re-
maining blast which escapes through said
apertures.

My improvement in this machine consists in performing the labor heretofore done by an attendant, by means of the auxiliary shaft K. The improvement consists in placing a revolving shaft or roller K, furnished with any suitable number of straight or curved fingers or projections o, o, o, immediately above the riddle N in the shoe G, said shaft or roller deriving its required motion from any convenient point, and being placed at or near the tail of the shoe, or at such point as in consequence of the blast from the fan failing to blow off the chaff and other foreign matter, the apertures in the riddle become choked, causing an accumulation of chaff etc., and preventing the grain from passing through the apertures in said riddle.

The feed board O, threshing cylinder A, fan F, return bottom M, riddle N, screen d, and other parts used in threshing and cleaning the grain, as well as the various modes of communicating the required motions to the several appurtenances above mentioned do not require to be particularly described, as they admit of a variety of modifications, and may be constructed and applied, in any of the ways now practiced.

I am aware that in Whitman's and other machines used for cleaning grain, rollers or cylinders provided with spikes, placed over vibrating sieves or riddles, and between the threshing cylinder A and endless belt of slats E employed for carrying off the straw, have been used for the purpose of beating the straw in order to separate the grain more effectually from the straw at the instant it leaves the threshing cylinder, at H, and also that the said roller of shaft has been employed to remove the greater portion of the chaff and other foreign matter from the sieve or riddle by throwing it up and carrying it off along with the straw on the endless carrier E. This roller or shaft H, when so placed and used for the purpose of separating the remaining grain from the straw by beating it after it leaves the threshing cylinder I do not claim; neither do I claim said roller or shaft, when used for re-

moving the greater portion of the chaff and other foreign matter from the riddle by throwing up and carrying it off along with the straw on the endless carrier E.

My invention consists in the revolving shaft or roller K, furnished with any suitable number of straight or curved fingers or projections o, o, o, working immediately above the riddle N, said roller or shaft, deriving its required motion from any convenient point, and being placed at or near the tail of the shoe where in consequence of the blast from the fan F failing to blow off the chaff, the apertures become choked, preventing the grain from passing into the shoe, and causing an accumulation of chaff and other substances at the tail of the riddle, which obstruction in machines heretofore constructed, in general, has been obviated by an attendant stirring and removing the chaff with a stick. This work I perform by means of the shaft K, the continuous circular motion of said shaft K being combined with the laterally vibrating motion of the shoe G for the purpose of so dividing and agitating the chaff and other foreign matter (at that point of the riddle, where the blast from the fan F becomes so nearly exhausted that the apertures in the riddle become choked) that the apertures are kept open, the remaining grain passing freely through the riddle into the shoe, while the chaff, and other foreign matter, being kept in motion by this shaft, is blown off at the tail of the riddle N by the slight remaining blast which escapes through these apertures.

Having thus fully described the nature of my improvement in machinery for threshing and cleaning grain and shown the operation thereof, what I claim therein as new, and desire to secure by Letters Patent is—

The application of the auxiliary shaft K constructed in the manner, and employed for the purpose, above described and set forth.

W. H. ORR.
